US0D1065174S

(12) **United States Design Patent** (10) **Patent No.:** **US D1,065,174 S**
(45) **Date of Patent:** **** Mar. 4, 2025**

(54) **KIOSK FOR PROCESSING ELECTRONIC
DEVICES**

(71) Applicant: **ecoATM, LLC**, San Diego, CA (US)

(72) Inventors: **Babak Forutanpour**, San Diego, CA (US); **Ted Ray Gooding**, San Diego, CA (US)

(73) Assignee: **ecoATM, LLC**, San Diego, CA (US)

(**) Term: **15 Years**

(21) Appl. No.: **29/804,021**

(22) Filed: **Aug. 17, 2021**

(51) **LOC (15) Cl.** **14-02**

(52) **U.S. Cl.**

USPC **D14/307**

(57) **CLAIM**

The ornamental design for a kiosk for processing electronic devices, as shown and described.

DESCRIPTION

FIG. 1 is a top, front, right perspective view of a kiosk for processing electronic devices.

FIG. 2 is a front elevation view thereof.

FIG. 3 is a back elevation view thereof.

FIG. 4 is a right-side elevation view thereof.

FIG. 5 is a left-side elevation view thereof.

FIG. 6 is a top plan view thereof; and,

FIG. 7 is a bottom plan view thereof.

The broken line showing of a kiosk is included for the purpose of illustrating portions of the article and forms no part of the claimed design.

1 Claim, 4 Drawing Sheets
